UNITED STATES PATENT OFFICE.

JOHN BENSE AND ABRAHAM SIEVERT, OF ROCKY RIDGE, OHIO.

POST-HOLE AUGER.

SPECIFICATION forming part of Letters Patent No. 317,491, dated May 12, 1885.

Application filed November 12, 1884. (No model.)

To all whom it may concern:

Be it known that we, JOHN BENSE and ABRAHAM SIEVERT, citizens of the United States, residing at Rocky Ridge, in the county of Ottawa and State of Ohio, have invented new and useful Improvements in Post-Hole Augers, of which the following is a specification, reference being had to the accompanying drawings.

10 Our invention relates to post-hole augers; and it consists in the construction and novel arrangement of parts, as will be hereinafter fully described and claimed.

In the drawings, Figure 1 is a view in perspective of the machine in the working position. Fig. 2 is a side view of the machine in position for drawing out of the post-hole. Fig. 3 is a longitudinal central section showing the machine in the position for knocking the dirt from the auger. Fig. 4 is a rear view, and Fig. 5 is a transverse section on the line *xx* in Fig. 4.

Referring by letter to the accompanying drawings, *A* designates the platform of the machine, which is mounted on two runners, *B*, and two wheels, *C*, and is provided with handles *D*, by which to move it from place to place.

D' D' are uprights rising from the platform *A* near its front end. These uprights *D' D'* are connected at their upper ends by a girder, *E*, and are provided with metal ways *F* for the sliding frame *G*, which carries the gearing by which the auger is operated. The metal ways *F* extend from the top of the girder *E* to the sills of the platform *A*.

The handles *D* are mortised through vertically at *D²*, and in said mortises *D²* are pivoted vertical rack-bars *H*, which extend up 40 as high as the top of the girder *E*. The upper ends of the vertical rack-bars *H* are kerfed at *H'*, and in these kerfs are pivoted the connected dogs or catch-arms *I*. The arms *I* work in kerfs *I'* in the girder *E*, and are prevented from leaving said kerfs *I'* by staples *I²*, driven over them into the girder *E*.

The uprights *D' D'* and girder *E* are strengthened by an arched brace, *E'*, and a wear-plate, *E²*, traverses the rear face of the girder *E*, and prevents the dogs *I* from wearing the girder *E*. The girder *E* is recessed vertically in

its rear face at *E³*, and in this recess *E* a spring-catch, *J*, plays.

G designates a sliding frame, which carries the gearing by which the auger is operated. The sliding frame *G* is provided with lugs *d*, which engage the metal ways *F* and guide said sliding frame when raised and lowered. The transverse shaft *L* of the gearing, by which the auger *M* is operated, is provided, 55 near each end, with a pinion, *N*, which engage the pivoted rack-bars *H* when the auger is to be elevated out of the post-hole, and this shaft *L* is also provided with a bevel gear-wheel, *P*, engaging a similar gear-wheel, *P'*, on the upper end of the auger-shaft *P'*, which latter is journaled in bearings *Q* on the swinging frame *R*, hinged upon the transverse shaft *L* of the sliding frame *G*. The lower transverse bar, *G'*, of the sliding frame *G* is 60 provided with spring-catches *G²*, which engage the lower bar of the swinging frame *R*, and hold the frame *R* in its normal position until it is designed to knock the dirt from the auger, at which time the sliding frame *G* is at 65 the upper end of the ways, and is locked in place by the spring-catch *J*. While in this position the cranks can be operated to knock the auger against the rod *R'* between the handles, and thus jar the dirt that has adhered to 70 the auger.

The transverse shaft *L* is provided, near one of its bearings, with a cross-pin, *U*, (see Fig. 1,) which engages a spring-arm, *V*, (see Fig. 4,) projecting upwardly from the upper cross-bar, 75 *W*, of the swinging frame *R*, and prevents the driving-shaft *L* from turning backward, and causes the auger to be swung out against the rod *R'*, against which it may be repeatedly knocked to shake the dirt from the auger, 80 should it adhere thereto.

Springs *X* are provided near the lower ends of the uprights, and bear against the pivoted rack-bars near their lower ends, and force them out when the catch-arms *I* are released 85 from the keeper on the girder.

Having thus fully described our invention, what we claim as new, and desire to secure by Letters Patent of the United States, is—

1. The combination, with the platform having the vertical ways connected by a girder having a spring-catch, of the hinged rack-bars

having the hinged connected dogs, and the sliding frame with the transverse crank-shaft with pinions and miter-gear, and the swinging frame having the auger-bit with a miter-gear at its upper end, substantially as specified.

2. The combination, with the transverse shaft L, having bearings in the sliding frame G, and provided with the cross-pin U, of the spring-arm V, secured to the cross-bar W of frame R, substantially as specified.

3. The combination, with the truck-frame having vertical ways and a cross-rod, R', of the hinged rock-bars, hinged connected dogs, the sliding frame, the hinged frame, the auger-bit, and gearing, substantially as described, for operating the auger-bit, as set forth.

4. The combination, with the truck and its vertical ways, of the hinged rack-bars H, springs for forcing the said bars outward, pivoted dogs or catch-arms I, staples I², holding the dogs in place, the transverse shaft having

pinions to engage the rack-bars, the auger-shaft, and gears on the latter and on the transverse shaft, as and for the purpose set forth. 25

5. The combination, with the truck having the vertical ways and a cross-rod, R', of the sliding frame moving on the ways, and a swinging frame carrying the auger and attached to the sliding frame, as and for the purpose set forth. 30

6. The combination, with the truck having the vertical ways, of the sliding frame carrying the swinging frame with the auger, and spring-catches for the swinging frame, as set forth. 35

In testimony that we claim the foregoing as our own we have hereto affixed our signatures in presence of two witnesses.

JOHN BENSE.
ABRAHAM SIEVERT.
